UNITED STATES PATENT OFFICE.

ALONZO D. FAULKNER, OF MEYERSDALE, PENNSYLVANIA, ASSIGNOR TO
GEORGE H. DUNCOMBE, OF MEYERSDALE, PENNSYLVANIA.

RAILWAY-CAR CHOCK.

SPECIFICATION forming part of Letters Patent No. 703,906, dated July 1, 1902.

Application filed February 4, 1902. Serial No. 92,568. (No model.)

To all whom it may concern:

Be it known that I, ALONZO D. FAULKNER, a citizen of the United States, residing at Meyersdale, in the county of Somerset and State 5 of Pennsylvania, have invented new and useful Improvements in Railway-Car Chocks, of which the following is a specification.

This invention relates to railway-car chocks, and has for its object to provide a cheap, durable, and efficient device of the character described which may be readily applied to a track for chocking the wheels of the car at any point thereon.

A further object is to provide a device which 15 is portable and may be used on rails of varying degrees of thickness.

The device is intended to be used at any point upon the rails for chocking the car and prevent its moving in one direction. It is intended to employ the device particularly with 20 cars where a grade is provided and where the brakes fail to hold the car, particularly when loaded, in an effectual manner.

Further advantages, as well as the peculiar 25 construction of the device and the manner of using the same, will appear as the nature of the invention is better understood.

In the drawings, Figure 1 is a perspective view of the device ready to be applied. Fig. 30 2 is a side elevation of a rail, showing the invention applied thereto; and Fig. 3 is a sectional view on the line 3 3 of Fig. 2.

The reference-numeral 1 designates a block provided with a segmental curved end 2, 35 formed to correspond with the contour of the car-wheel, which is adapted to rest against said curved portion snugly. The entire edge of the block is preferably bound by a strip of metal 3, which may be replaced from time 40 to time as it becomes worn. On either side of the block and near the curved end thereof are countersunk vertically-arranged parallel plates or jaws 4, which project a slight distance below the base of the block, so as to 45 overlap the sides of the rail, as shown in Fig. 2. Near the rear end of the block are two similar plates or jaws 5 and 6, which are loosely secured thereto by a bolt 7, so that the lower ends of the jaws are expandable and retractable to accommodate the device to rails of varying widths. A bifurcated lever 8 is secured

to the block and preferably to the sides of the plates 4, and this lever straddles the block, so that by lowering the end 9 thereof the bifurcated portions will bear against the plates 55 or jaws 5 and 6 and cause them to firmly impinge against the sides of the rail, thereby forming a lock to retain the device rigid with relation to the rail.

In Figs. 2 and 3 the chock is illustrated as 60 being applied to the smallest form of rail, and therefore the lever is illustrated as being on a horizontal plane. However, if the device is applied to a rail of greater width the lever will assume a position less than a right angle 65 to that of a rail, according to the width thereof. In actual practice it has been found that the weight of the lever is sufficient to securely lock the device through the medium of the jaws rigid with relation to the rail, and 70 by moving the device at any predetermined point the car may be effectually chocked and any tendency to slide down the grade, owing to ineffectual brakes or other causes, will be obviated.

It will thus be apparent that I have provided a cheap, durable, and efficient car-chock which may be readily applied to and detached from the rail at any convenient point without the use of tools or implements 80 of any kind, and while I have specifically described the exact details of construction of the preferred form of this device I would have it understood that I reserve the right to make such slight changes and alterations as might 85 suggest themselves from time to time without departing from the spirit of this invention.

Having thus fully described my invention, what I claim, and desire to secure by Letters 90 Patent, is—

1. A car-chock having two pairs of jaws, one pair being rigid, and the other pair expandable and retractible, and means straddling the last-named jaws and designed to 95 force them against the sides of the rails.

2. A car-chock comprising a rigid pair of jaws and an expandable and retractible pair of jaws, and a bifurcated lever designed to straddle the last-named pair of jaws and force 100 them against the sides of a rail.

3. A car-chock comprising a body, a pair

of plates carried thereby and having depending ends designed to overlap the tread of a rail, plates secured to the other end of the body and loosely mounted thereon to form 5 expandible and retractible jaws, and means for forcing said plates against the sides of the rail whereby the body will be rigidly secured thereto.

4. A car-chock comprising a body, a pair 10 of vertically-arranged plates carried thereby and having depending ends adapted to overlap the tread of a rail, a pair of vertically-ar-

ranged plates secured to the body and loosely carried thereby, said plates also having depending ends adapted to fit over the tread of 15 a rail, and a bifurcated lever designed to straddle the block and last-named plates and force them in rigid contact with the rail.

In testimony whereof I affix my signature in presence of two witnesses.

ALONZO D. FAULKNER.
